APPARATUS FOR COATING BATHING CAPS

Filed Sept. 10, 1948

UNITED STATES PATENT OFFICE

2,607,317

APPARATUS FOR COATING BATHING CAPS

Albert E. Sidnell, Akron, and Theron T. Thompson, Barberton, Ohio, assignors to Seiberling Latex Products Company, Barberton, Ohio, a corporation of Ohio

Application September 10, 1948, Serial No. 48,578

6 Claims. (Cl. 118—107)

1

This invention relates to a new and improved device for processing rubber products, and more particularly the varnishing operation for finishing rubber bathing caps.

In the manufacture of rubber bathing caps the final production operation consists of coating the cap with a varnish to seal the outside surface of the cap thereby imparting to the surface a glossy finish. The usual production method for this operation is to stretch the cap over a wooden form block and brush the varnish over the surface manually.

The object of this invention is to provide mechanical means for accomplishing the above described operation thereby insuring the manufacture of a more uniform product at a much faster rate than can be done by the present manual method.

The bathing cap varnisher of this invention includes a form-block mounted at the end of a shaft with one or more brushes adapted to be moved into and out of contact with a cap placed on the form. Spray guns or other means are provided for applying the varnish to the caps. The means for applying the varnish and moving the brushes to and from the cap are properly coordinated.

In the preferred varnisher illustrated in the drawings there are three brushes spaced evenly about the form block. One is a trifle longer than the other two and makes contact with the portion of the cap which covers the axis of the form block. These brushes are mounted on pivoted arms which are actuated by slotted cams in a cam block. Moving the cam block to the rear presses the brushes to the cap placed on the form block. Moving it forward lifts the brushes out of contact with the cap. This cam block surrounds the shaft on which the form block is mounted. A clutch is mounted to move with the cam block. On moving rearwardly it contacts a sheave block and the shaft is rotated at high speed. The form block rotates with it. Forward movement brings it into contact with a brake which rapidly brings the cap to rest.

The invention will be further described in connection with the accompanying drawings in which:

Figure 1 is a side elevation, partially broken away, showing the location of the respective machine elements at a time during the operating cycle when the brushes are engaged;

Figure 2 is a fragmentary view taken on the line 2—2 of Figure 3 showing the horse-shoe brake plate, the clutch yoke and the means for slidably

2

mounting the clutch yoke base in the guideways, all as will be more fully explained in what follows;

Figure 3 is a side elevation similar to Figure 1 showing the location of the respective machine elements when the brushes are disengaged from the form block, parts irrelevant to the action of the machine being omitted for clarity;

Figure 4 is a schematic diagram of the piping system including the necessary valves, etc. to control the operation.

Referring to Figures 1 to 3 of the drawings, a form block 10 is keyed to the end of a horizontal shaft 11 mounted between a standard pillow-block bearing 12 and a ball bearing located in the center of the vertical spider 13, both of which are mounted on a steel table top 14 which is supported on the frame 14'. Three brushes 15, shaped to the contour of the form block are positioned at equal intervals around the form block and are removably and adjustably fastened into handles or control arms 16 which are pivoted on the vertical spider 13. Adjustment is made possible by the brushes being held between the bolts 17 and the bolts 18 which are threaded into tapped holes in the control arms 16. The opposite ends of the control arms contain the pins 19 which are slidably inserted in the slotted cam plates 20. There are three of these cam plates 20 welded to the periphery of a cylinder 21 which is concentrically fitted over the horizontal shaft 11 and free to slide over the shaft. The cam block 22 provided with cam slots 22' is secured to a vertical circular plate 23 also fitted slidably and concentrically around the shaft 11, the plate's base being welded to a flat slideable plate 24 mounted between two guideways 25. The slideable plate 24 extends rearwardly of the machine.

The base of the clutch yoke 30 is slidably mounted in the guideways 25, and is attached to the slideable plate 24 by means of two coil springs 31 interposed between the clutch base and a block 32 welded to the rear extremity of the slideable plate 24. The sliding action of the slide plate 24 is transmitted to the clutch mechanism through the coil springs, the springs effectively dampening any shocks occurring when the friction clutch 35 engages the sheave block 36 which is driven by V-belts 37. The V-belts are driven by any suitable driving means such as an electric motor 38, a reduction gear 39, and a V-belt driver sheave 40.

The slider plate 24 is actuated by an air cylinder 45 located beneath the steel table top 14 with the cylinder piston rod 46 parallel to the shaft

11. The piston rod is secured to a vertical bar 47 which is welded to the forward extremity of the slideable plate 24. The bar 47 passes through a slot 48 parallel to the shaft 11, cut out of the table top. The vertical bar 47 transmits the reciprocating motion of the air-cylinder piston rod to the slideable plate 24.

While the brushes 15 are in contact with the revolving form block 10, the cam block 22 is in its extreme back position and the pins 19 are at the outmost point in the slotted cams as indicated in Figure 1. The clutch mechanism as well as the cam block being secured to the slideable plate 24, the clutch moves with the cam block and at the point of the cycle that the brushes are in contact with the form block, the clutch is engaged with the sheave 36. The form block 10 rotates with the shaft 11. The clutch is slidably fitted to shaft 11 over the key 50, and when the clutch engages sheave 36 the shaft 11 and form block are rotated at high speed.

When the air cylinder piston rod is forced forward, the cam block 22, cooperating with the piston rod movement slides forward in the guideways 25. The arm pins 19 travel down their respective cam slots to the inner points of the slots causing the brushes to lift from the form block 10. Figure 3 illustrates this stage of the cycle. The clutch 35 is simultaneously disengaged from the sheave 36 and brought into contact with friction plate 53 on brake plate 54 attached to a horse-shoe shaped plate 55 which encircles the shaft 11 and the reduced forward portion 56 of the clutch guideways 25 as clearly shown in Figure 2. The portion 56 of the clutch fits within the horse-shoe brake.

A suitable sheet metal hood 60 encloses the form block 10 and the brushes 14. This hood has an opening 60' in its front side to permit access to the form block so that a bathing cap may be readily placed on or removed from the form block. Two standard spray guns 61 are strategically located in the hood to spray a cap with varnish which is later to be spread over the cap by the brushes. The spray guns 61 are fed through conduit 62 from the varnish reservoir 62 which may be located in any convenient position. A tray or other suitable means is provided in the bottom of the hood to dispose of excess spray collecting therein. Suitable duct work, not shown, containing an induced draft fan purges the hood of the excess atomized varnish and toxic fumes that may be evolved during the operation.

The air control system is schematically shown in Figure 4. A valve 70 connects the piping system with a standard industrial compressed air line, preferable pressure being about 85 p. s. i. A suitable water filter or separator 71 is positioned in the line. The high pressure air line 72 divides into two conduits, 73 and 74. Conduit 73 divides and enters the respective chambers of two three-way diaphragm control valves 75 and 76 which operate the air cylinder. Conduit 74 leads into a pressure reducing valve 77. The air passing through valve 77 is reduced to a pressure of preferably about 40 p. s. i. and passes into the chamber of a valve 78 enclosed in the timer box 80. The valve stem of valve 78 is actuated by a suitable timing cam (not shown) in the timer box which controls the air flow through conduit 81 into the diaphragm chambers of the control valves 75 and 76.

Conduit 84 which leads from the low pressure air line 85 beyond the valve 77 is connected to

a chamber of the solenoid valve 88. The solenoid valve 88, actuated by switches (not shown) automatically controlled in the timer box 80 permits the low pressure air to pass through conduits 89 to the spray guns 61 at the proper point of the cycle.

The complete operating cycle will now be described starting with the shaft 11 and form block in the stalled position shown in Figure 3. The motor 38 is rotating the sheave block 36 at all times. The operator stretches a bathing cap on to the form block and presses the button 90 which actuates the timing mechanisms. This first actuates a switch which opens solenoid valve 88. This causes low pressure air to pass to the spray guns 61 which spray varnish on to the cap before it starts revolving. At the proper time in the cycle the timer again actuates the valve 88, this time closing it. Substantially simultaneously, the timer will cause valve 78 to open permitting the passage of air through conduit 81 into the diaphragm chambers of control valves 75 and 76. These are three-way valves. When air presses on the diaphragm of valve 76 the three-way valve (not shown) in its base is turned to pass air thru its base into the pipe 91 and thence into the air cylinder to force its piston rearwardly. This moves the slideable plate 24 to the rear together with the cam block 22 and clutch mechanism which is attached to it. This movement of the cam block presses the brushes on to the cap. The closing of the clutch starts the shaft 11 revolving. This revolves the hat and the varnish is spread uniformly over its surface. During this interval the pressure on the diaphragm of valve 75 turns the three-way valve in its base to the same position as that in the base of the valve 76. However the pressure line leads into the bottom of valve 75 and into the side of the base of valve 76. Thus pressure causes the exhaust from the air cylinder passing through the line 92 into the base of valve 75 to be vented through the opening in the side of the base of valve 75 corresponding to the opening in the base of valve 76 to which the pressure line is fastened.

Pressure is maintained on the line 81 until the varnish has been uniformly spread on the bathing cap and sufficient of the solvent has evaporated from it to permit handling of the cap for removal and packaging. At the end of this interval the timer again actuates the valve 78, but this time to relieve the pressure on the diaphragms in valves 75 and 76. The valve in the base of valve 75 turns and pressure is applied through line 92 to the piston of the air cylinder. The three-way valve in the base of valve 76 turns to connect line 91 with the opening in the bottom corresponding to the opening in the bottom of valve 75 in which the pressure line is connected. This opening in the bottom of valve 76 serves as an exhaust. The slideable plate 24 is moved forward, sliding the cam block 22 so as to lift the brushes, and at the same time bringing the clutch against the brake surface 55. This instantly stops the rotation of the shaft 11 and the form block. The operator removes the cap and the cycle is complete. An untreated cap is immediately placed on the form block, the timer switch 90 is pressed, and the operation is repeated.

Modifications may be made in the structure disclosed. The number of brushes and spray guns may be changed. The form block may be rotated during the application of varnish.

5

The air cylinder, motor, solenoid valve, etc. may be replaced by other usual mechanisms for accomplishing like results.

What we claim is:

1. Apparatus for applying liquid surface coating on a bathing cap which apparatus includes a form block over which a bathing cap can be stretched, which form block is adapted to be rotated on a central axis, a hood enclosing the form block, mounted adjacent the form block inside the hood a brush and means for moving the brush toward and away from the form block, an opening in the hood to permit access to the form block for placing and removing the bathing cap, liquid atomizing means inside the hood adapted to direct atomized liquid on the cap on the form block, means for supplying liquid to the atomizing means, and timing means and means operated thereby which (1) actuates the atomizing means for a predetermined interval whereby a quantity of liquid is deposited on the cap, and (2) actuates the means which moves the brush toward the form block and into contact with a cap on the form block after liquid is applied thereto, which brush is adapted to spread the liquid evenly over the surface of the cap during rotation of the form block.

2. A bathing cap varnisher which includes a hood, a form block therein to hold a bathing cap while being varnished, an opening in the hood through which the bathing cap can be readily placed on and removed from the form block, means for rotating the form block, a reservoir for varnish and means for supplying varnish therefrom and applying it to the surface of the bathing cap placed on the form block, means mounted inside the hood adjacent the form block and adapted to be moved into contact therewith to spread the varnish on the surface of a cap on the form block while the form block is rotating, cam means engaged with the spreading means to move the spreading means into contact with the cap, means for moving the cam whereby the spreading means is moved, and timing means and means operated thereby which actuates the varnish-applying means and then actuates the cam-moving means.

3. A bathing cap varnisher which includes a frame, a shaft rotatably mounted in the frame, fixed to one end of the shaft a form block adapted to hold a bathing cap in stretched condition, means fastened to the frame for applying varnish to a cap located on the form block, a hood enclosing the form block except for an opening to permit access to the form block so that a bathing cap may be readily placed on or removed from the form block, means on the frame for rotating the shaft, brushes curved to fit the contour of the form block which brushes are located around the form block, supporting means for each brush pivotally mounted on the frame adjacent the form block, a cam surrounding the shaft and held against rotation and slidably longitudinally of the shaft, cam-engaging means on the brush-supporting means which contact cam surfaces on the cam, and means on the frame for reciprocating the cam longitudinally of the shaft, the cam surfaces being adapted to pivot the brush-supporting means to swing the brushes toward and away from the form block as the cam is moved in opposite directions along the shaft.

4. A bathing cap varnisher which includes a frame, a shaft rotatably mounted on the frame fixed to one end of the shaft a form block adapted

6

to hold a bathing cap in stretched condition, means fastened to the frame for applying varnish to a cap located on the form block, a hood enclosing the form block except for an opening to permit access to the form block so that a bathing cap may be readily placed on or removed from the form block, a brush curved to fit the contour of the form block, brush supporting means pivotally mounted to swing the brush toward and away from the form block, a sheave rotatably fastened to the shaft, a brake maintained in spaced relation to the sheave, positioned between the sheave and the brake a clutch keyed to the shaft and adapted to slide longitudinally thereof, a cam mounted on the frame slidably with respect to the shaft and having therein a cam surface coactively connected to the brush supporting means, and power means connected with the clutch and with the cam which power means is operable to move the clutch and cam simultaneously longitudinally of the shaft in one direction to engage the clutch with the sheave to thereby rotate the shaft and to swing the brushes into contact with the cap.

5. A bathing cap varnisher which includes a horizontal shaft, a hood open at the front with the forward end of the shaft entering the rear of the hood, a form block in the hood fastened to the forward end of the shaft, a varnish reservoir, spray means inside the hood for spraying varnish onto a bathing cap stretched over the form block, varnish-conveying means connecting the spray means with the reservoir, a sheave rotatably mounted on the shaft to the rear of the hood, drive means for rotating the sheave, brushes each having the contour of the form block arranged around the form block, brush-supporting means pivotally mounted and operable to swing the brushes away from the form block and toward it after varnish has been sprayed on a cap placed on the form block, adjustable means for fastening each brush to its respective supporting means so that the position in which the brush contacts the form block may be changed, surrounding the shaft a stationary brake spaced a short distance from the sheave, between the brake and the sheave a clutch slidably keyed to the shaft, a cam slidably mounted around the shaft and held against rotation, slotted cam surfaces in the cam engaged with portions of the brush-supporting means to operate the brush-supporting means, and slideable means fastened to both the cam and the clutch which means is movable parallel to the shaft in order (a) to move the clutch into contact with the sheave thereby rotating the shaft and the form block, and simultaneously moving the cam so that the slotted cam surfaces thereon pivot the brush-supporting means to bring the brushes into contact with the cap, and (b) to move the clutch in the opposite direction where it contacts the brake and stops the shaft rotation and also moves the cam to lift the brushes away from the cap on the form block.

6. Apparatus for applying coating on a bathing cap which apparatus includes a frame, a form block over which a bathing cap may be stretched, means fastened to the frame for applying varnish to a cap located on the form block, a hood enclosing the form block except for an opening to permit access to the form block so that a bathing cap may be readily placed on or removed from the form block, a shaft rotatably mounted in the frame upon which the form block is fastened, means on the frame for rotat-

ing the shaft, a cam slidably mounted around the shaft, a brush supported by the frame adjacent the form block, supporting means for the brush engaged with the cam, and means on the frame for imparting reciprocating movement to the cam on the shaft to bring the brush into and out of contact with the form block during operation of the apparatus.

ALBERT E. SIDNELL.
